MARJORIE C. EDMUNDSON, OF SAN PEDRO, CALIFORNIA

SURGICAL BANDAGE

Application filed March 22, 1928. Serial No. 263,842.

This invention relates to surgical bandages, and particularly to a novel construction of individual bandage, and to a strip arrangement of individual bandages adapting any number of such bandages to be put up in roll form for convenient separation and use as occasion requires.

In the bandaging or dressing of sores and wounds it is customary to employ a band or dressing of antiseptic gauze which is secured in position by strips of surgical tape or plaster. The gauze and plaster are usually put up in roll form and amounts sufficient for a particular dressing are cut off from the rolls at the time of use. This often involves a waste of material and is a time consuming operation because of the necessity of partially unbinding the rolls, cutting off the desired portions thereof, trimming such portions, separately applying the gauze and tape to form the dressing, and rewinding the rolls. Besides, in the frequent operations of winding and unwinding the rolls, unused portions of the gauze and tape are exposed to the atmosphere and are liable to become soiled and contaminated, with obvious disadvantages.

The object of my invention is to provide simple, reliable and efficient means for overcoming these objections, and my invention consists in the provision of an independent bandage of any size suitable for use and which comprises a section of gauze fabric with which are combined the adhesive strips for holding the same applied, or of a series of such gauze sections united by adhesive strips so as to form a multiple bandage in strip form and capable of being subdivided into separate bandages for use as required, which multiple bandage may be wound into the form of an ordinary roll so as to be packaged in the usual manner. With this construction a bandage of the size required may be quickly selected and applied with a saving of time and labor over the customary practice and without waste or liability of exposing unused material to the danger of contamination.

In the accompanying drawing,—

Figure 1 is a plan view of a portion of a multiple bandage roll strip embodying my invention.

Figure 2 is a view of the strip as wound in roll form.

Figure 3 is an obverse plan view of an individual bandage as separated from the roll strip for use.

Figure 4 is a similar view of a modified form of bandage.

In carrying my invention into practice, I provide a multiple bandage in strip form, and which comprises any desired and suitable number of individual bandages separable from the strip for use as occasion requires. The multiple bandage, in the form disclosed, consists of a series of bandage sections 1, preferably made of gauze fabric, and arranged with their adjacent edges in spaced relation to each other, said bandage sections being held connected and in spaced relation by parallel longitudinal carrier strips 2. Each of these carrier strips is made of adhesive or surgical tape, which is provided, as usual, with an adhesive face 3 and a non-adhesive face 3'.

The fabric sections 1 may be of rectangular, oblong rectangular or other suitable form and each of a size to provide a prescribed size of dressing. The outer faces of these fabric strips are secured to the adhesive faces 3 of the carrier strips 2 along their longitudinal edges and extend over approximately one-half the distance of the width of the strips 2 so as to leave portions 4 of the faces 3 projecting laterally beyond the longitudinal side edges of the sections 1. These projecting portions 4 of the strips 2 are thus adapted to be used to secure the bandage section along its longitudinal edges in place upon the person of the patient. The fabric sections 1 are or may be spaced with their end edges the same distance apart throughout the length of the multiple bandage, and the portions of the strips 2 which extend across the gaps between the end edges of the fabric sections are adapted to be severed along the dotted lines 5 in the successive separation of the individual bandages from each other. When an individual bandage is separated from the multiple strip a type of individual bandage such as shown in Figure 3 is produced, which bandage comprises a

fabric bandage section 1, along the longitudinal edges of which extend securing strips having adhesive faces partially secured to the longitudinal edges of the bandage section and partially projecting therefrom to provide the securing portions 4. These strips 2 have end portions 6 in the form of tabs with adhesive faces for securing the bandage at its ends to the person of the patient. Such a bandage when applied will be firmly and securely held in position to cover and protect a wound, sore, scald or burn, while, at the same time, its end portions between the projecting pairs of tabs 6 will be sufficiently free from connection with the body of the patient to allow of the degree of ventilation of the affected part considered to be desirable.

Multiple bandages of the construction above set forth may be made with bandage sections of different sizes within any given range, and such a bandage may be wound in roll form, as shown in Figure 2, for convenience in packing and transportation and the putting up of the device in a desirable form for use, so that the individual bandages may be successively unwound and separated for use, making it unnecessary to expose more than this one particular bandage during such operation. By this means a bandage of suitable size for any purpose may, within a very short period of time be removed from a protective container and applied for use, without exposing any of the remaining bandage sections to exposure and possibility of contamination. Instead, however, of making the bandages in multiple strip form, as shown in Figure 1, for winding into roll form, as shown in Figure 2, individual bandages, of the type disclosed in Figure 3, ready prepared for use, may be employed and sold in protective envelopes, any suitable number of which may be placed in a package for dispensation, so that in this case also a bandage of the exact size required may be removed and applied in a very short space of time and without the necessity of exposing other bandages.

In Figure 4 I have shown a slightly modified form of bandage which may be used and found desirable under some conditions, where it is desired to add to the security of attachment of the bandage to the person of the patient. The construction here is the same as that previously described except that an additional strip 7 is applied transversely to the outer or rear face of the bandage section 1 and has projecting attaching ends or tabs 8 for additionally securing the bandage beyond the attaching surfaces 4 of the strips 2.

The advantages of my invention will be readily understood from the foregoing description. As heretofore explained, in making ordinary bandages it is customary to unwind the gauze fabric and adhesive tape from separate rolls, to cut off sufficient portions

thereof to form the bandage and then apply these to form the bandage. This frequently results in the waste of material, as it is not always possible to remove just the exact amounts of material needed. It also results very often in the exposure of portions of the material unused at the time, with the result that these are soiled or become contaminated by exposure to the atmosphere or by other causes. My invention obviates all of these objections, enables a bandage of the exact size required, and without waste, to be selected for use and applied without loss of time and without danger of undesirably exposing bandage material not used. It also provides a means whereby bandages of all sizes may be furnished at a comparatively low cost, since it is evident that the bandages may be manufactured in a complete manner by machine methods. It will be observed that the arrangement of the strips 2 or 2 and 7 is such that the adhesive faces of these strips when wound in roll form, will be held spaced by the fabric sections 1, so that such faces of the strips can not possibly become stuck together.

Having thus fully described my invention, I claim:

1. A multiple bandage in strip form comprising a plurality of gauze fabric sections arranged with their juxtaposed end edges in spaced relation, and strips of surgical tape extending across the gaps between the fabric sections and along the side edges of said fabric sections and having their adhesive surfaces secured to the said side edges of the fabric sections between the longitudinal centers and inner side edges of said strips, whereby the portions of tape extending across the gaps may be transversely severed to separate the gauze sections from each other.

2. A multiple bandage in strip form comprising a plurality of gauze fabric sections arranged with their adjacent edges in spaced relationship, and attaching strips uniting the sections in strip form and adapted to be severed between the fabric sections to separate a fabric section from the strip and to serve as means for attaching said fabric section to a part of the human body to which it is to be applied.

In testimony whereof I affix my signature.

MARJORIE C. EDMUNDSON.
